UNITED STATES PATENT OFFICE

ALBERT J. LOEPSINGER, OF PROVIDENCE, RHODE ISLAND, ASSIGNOR TO GENERAL FIRE EXTINGUISHER COMPANY, OF PROVIDENCE, RHODE ISLAND, A CORPORATION OF DELAWARE

QUARTZ BULB

Application filed November 30, 1929. Serial No. 410,751.

My invention relates to improvements in quartz bulbs. More especially it has to do with a quartz bulb whose cells or voids in its wall are disposed in ever-changing directions, more or less transverse to its longitudinal axis.

Bulbs heretofore made from quartz have had air cells or voids in their walls, more or less attenuated, and appearing as a myriad of long straight striae of exceedingly small cross section. This follows from the fact that when either quartz sand or quartz crystals are fused the resulting molten mass has a large number of cells, containing either a gas or a liquid, which do not give up their contents because while the quartz may be brought to a viscous state it can not be made liquid enough for the contents of these cells to escape by bulbing to the surface. Accordingly the cells remain in the molten mass and if this be merely drawn straight out to form a tube as has been the practice, the same cells will appear in the wall of the tube, albeit they are necessarily stretched by the pulling and made smaller in cross section. Likewise in bulbs made from such tubes, the walls thereof will also be characterized by the same striae as were present in the tube.

These cellular striae, whether empty or filled with air or other fluid, are elements of weakness in the finished bulb and are particularly undesirable in bulbs subjected to internal pressure because it has been observed that on the rupture of such bulbs so used the plane of cleavage most frequently follows one or more of these elongated voids. Since the latter have heretofore extended longitudinally of the bulb, in direction common with its recognized weakest dimension, these cells or voids in effect constitute incipient planes or lines of fracture and thereby materially weaken the bulb. This effect is so pronounced in bulbs made from quartz sand, where such cells are much greater in number, that such bulbs can not be relied upon where any great internal pressures are employed. For such work it has been deemed necessary, from the standpoint of reliability and efficiency, to use only bulbs made from quartz crystals. The molten mass resulting from fusing of

quartz crystals has a less number of cells or voids than is present in a molten mass of fused quartz sand, and these can be largely eliminated by carrying out the initial fusing in an electric furnace in which a vacuum is created, and then subsequently reheating the mass and subjecting it to pressure to drive out the voids. But this working and reworking of the material is expensive and if practiced in the production of bulbs for commercial use would render the cost of the latter entirely prohibitive. Consequently, as a practical matter, quartz crystals most free from cells have been carefully selected and then fused together, the resulting slug being then drawn out in the form of a tube from which the bulbs can be formed. There are still some cells present in the bulb, and, because of their straightline arrangement parallel to the axis of the bulbs, are always elements of danger and constitute incipient lines of weakness or planes of fracture not to be desired.

The present invention resides in a bulb which has its cells disposed in lines more or less transverse to its axis, and preferably of ever-changing direction. Such bulbs can be produced by drawing out the quartz in the form of a tube and twisting the tube about its axis as it is being drawn out or when it has been drawn out, or the quartz can be drawn out as a solid thread or ribbon and wrapped about a mandrel, each convolution adhering to the next and thereby producing a finished tube whose cells are arranged helically about its axis. A bulb made from quartz so handled will have the cells in its wall similarly disposed about its axis, and its resisting power to internal pressure will in consequence be greatly increased. In fact, bulbs having their cells so disposed are so much stronger than bulbs heretofore made, that the opaque form of quartz—the sand quartz—can now be used for bulbs where before only bulbs made from the choicest of crystals were deemed safe. And bulbs can be made of quartz crystals as they come, without any selection thereof whatever. As a result the bulb of the invention is not only much stronger and more re-

liable but is easier to produce and less expensive.

Figure 1 of the drawings shows a bulb embodying the features of this invention, the lines representative of the cells or voids being, for clearness, necessarily larger than the striae which they represent; and

Figure 2 illustrates an automatic sprinkler head employing such a bulb as a frangible strut.

10 The bulb A is made of quartz which initially may have been in the form of sand or crystals. The cells B in the wall of the bulb are disposed helically about the axis of the bulb in ever changing directions. This arrangement of the striae overcomes the danger of premature rupture heretofore present in bulbs having cells extending longitudinally of the wall in directions parallel to the axis of 15 the bulb. In consequence, bulbs like that illustrated can be relied upon to resist greater internal pressures and to act with more uniformity in their performance, because the improved disposition of the cells gives added 20 strength especially when the bulb is called upon to withstand internal pressure.

Such bulbs are particularly adapted for use as the frangible strut of an automatic sprinkler head. In such use the bulb contains a charge which upon rise of temperature to a predetermined degree generates an internal pressure sufficient to completely shatter the bulb. The charged bulb is mounted between a yoke C and a glass button D that 30 closes the opening of a diaphragm E secured between the yoke-ring F and the base G of the sprinkler. The latter is threaded so as to be screwed into a conduit of a sprinkler system, the conduit normally containing air or a fire extinguishing fluid under pressure. The head is assembled by first securing the diaphragm in place, the button is then seated within its hole of the diaphragm and a suitable bearing ring on plate H is placed in the hollow of the button to receive one end of the bulb A. The other end of the latter is then engaged by another bearing ring I attached 40 rotatably to an adjusting screw J which screws through the top of the yoke. This screw is then tightened, exerting pressure on the bulb and thus upon the button causing the latter to seat firmly on the diaphragm. When sufficient pressure has thus been established 45 the screw is pinned to the yoke, the deflector K added and the end of the screw riveted over to hold the deflector in place.

It will thus be seen that in this use of the bulb it is always under compressive stress applied externally at its ends. It is therefore important that it have no incipient lines of cleavage or fracture extending longitudinally along its wall between its ends. But it is even more important that bulbs be able to resist the internal pressure generated by the heating of its charge, until that degree of tem-

perature is reached at which the shattering of the bulb is desired. If it should split or partially fracture at some lower temperature, thereby permitting its charge to escape, the shattering pressure never could be realized and consequently the sprinkler would not open as planned. This, of course, would be fatal to the protective purpose of the device, and hence the importance of the present invention is apparent, for by eliminating the heretofore dangerous lines of cleavage, extending longitudinally of the bulb, and providing a bulb with its cellular striae disposed more or less transversely about its axis the bulb is well able to resist the rising internal pressure until the shattering degree is reached.

I claim:

1. A quartz bulb having its cellular striae disposed within its wall so as to intersect a plane containing the axis of the bulb.

2. A quartz bulb having its cellular striae disposed within its wall helically with respect to the longitudinal axis of the bulb.

Signed at Providence, Rhode Island, this 29th day of November, 1929.

ALBERT J. LOEPSINGER.
